UNITED STATES PATENT OFFICE.

ALEXANDER McDougall, OF DULUTH, MINNESOTA.

SPUD-ANCHOR FOR VESSELS.

1,320,642.

Specification of Letters Patent.

Patented Nov. 4, 1919.

Application filed April 20, 1918. Serial No. 229,874.

To all whom it may concern:

Be it known that I, ALEXANDER McDougall, a citizen of the United States, residing at Duluth, in the county of St. Louis and

5 State of Minnesota, have invented certain new and useful Improvements in Spud-Anchors for Vessels, of which the following is a specification, reference being had therein to the accompanying drawing.

10 This invention relates to anchorage devices for vessels and has special reference to shallow draft vessels such as navigate rivers.

On shallow navigable rivers and particularly the Mississippi, the pilots and aids to navigation are many times, sorely taxed for want of anchorage or suitable stopping places when during the night or in foggy or smoky weather, it becomes necessary to stop 20 the boat or tow.

Favorable landing places are invariably far apart and always more or less dangerous to make, frequently resulting in damage either to the steamer or tow or both and 25 often requiring very long hawsers to reach trees or stumps to tie to, all of which adds to the awkwardness, expense and danger accompanying such operation.

To avoid much, if not all of these objectionable and dangerous features is the primary object of my present invention and other objects and advantages will appear in the further description thereof.

In the accompanying drawings forming 30 part of this application and in which like reference characters represent like parts:

Figure 1 is a side elevation of a river steamer equipped with my improved anchorage device, illustrating one set thereof 40 in action.

Fig. 2 is an end elevation of Fig. 1.

Fig. 3 is a similar view showing the spuds raised and not in use as anchorage means, and

45 Fig. 4 is an enlarged elevation of one form of suspending the spuds.

The use of vertically reciprocal spuds for anchoring dredges or the like is old, but such devices would not be practical for use in anchoring a boat when in motion or when holding 50 a tow, as such spuds would be too rigid and unyielding for the purpose and would be much more liable to breakage and damage than my present invention.

55 In the drawings, 1 represents spuds suspended at or near their upper ends or heads

from the main deck of the hull 2 of the boat and over the sides thereof. Such attachment to the deck may be accomplished in any desired manner either by ropes, chains or other 60 practical means, one form of which is illustrated in Fig. 4 of the drawings.

These spuds may be made of wood or iron and a preferred form would be a combination of both, to better withstand the abuse 65 they might receive in engaging the bed of the river.

The spuds would be made of a length and size to suit the depth of water and other individual requirements, so as to extend at 70 least several feet below the bottom of the boat and engage the bed of the river. Adjacent the foot or lower end of each spud are securely attached two opposed wire lines or chains 3, one leading aft and the other forward 75 to the main deck of the boat where they may be made fast to suitable strong bollards or cleats as required. By these lines the spuds may be swung to any desired angle either forward or aft and there secured, 80 or brought up entirely out of the water alongside of the boat.

A boat may be equipped with one or more sets of these spuds as desired, they preferably being in pairs on opposite sides of the 85 boat and on large boats with tows, doubtless four spuds would be required.

By this arrangement, it is evident that when it is desired to anchor the boat, the spuds may be lowered to engage the bed of 90 the river and there firmly held by the lines 3 at any angle such engagement may result in, thus forming a secure anchorage for the boat and if such anchorage is employed at both ends of the boat, she may be still more firmly 95 held against movement or swinging motion.

In making such anchorage, the pilot would assist by checking the motion of the boat with her wheel sufficient for the spuds to securely hold, and may, if necessary, increase 100 their holding ability by crowding the boat against their angle of inclination when lowered and thus force them deeper into the bed of the river and in which position they may be securely held by the lines 3, the loosening 105 of which would instantly release the boat.

From the foregoing it is evident that I have devised a simple and practical form of anchorage for shallow draft vessels and one which materially augments the practicality 110 of river commerce in that it assures for a boat or a boat with a tow safe and

secure anchorage practically any place in the river where she may wish to lay to waiting weather or other favorable conditions for continuing her course and from where she 5 may quickly leave with the least inconvenience possible.

Having thus described my invention, what I claim as new and desire to secure by Letters Patent is:

- 10 An anchorage for vessels comprising spuds swingingly but non-reciprocably suspended from the vessel, a line attached near the free

end of each spud leading aft and a like line leading forward from the free end of the spud, whereby the latter may be rigidly held 15 at any desired angle fore and aft when engaging the bed of the river.

In testimony whereof I hereunto affix my signature in the presence of two witnesses.

ALEXANDER McDougall.

Witnesses:

A. C. DUNN,
S. GEO. STEVENS.
